UNITED STATES PATENT OFFICE.

PAUL EMILE AUGUSTIN CERETTE, OF PARIS, FRANCE.

CUPOLA.

1,000,737.

Specification of Letters Patent.

Patented June 9, 1914.

Application filed April 8, 1912. Serial No. 239,588.

To all whom it may concern:

Be it known that L'PAUL EMILE AUGUSTIN CERETTE, a citizen of the Republic of France, and residing at Paris, France, have invented
5 a certain new and useful Improvement in Cupolas, of which the following is a specification.

My invention relates to cupola furnaces for melting pig iron and the principal objects of my invention are to provide a furnace of novel construction designed to secure more efficient fuel combustion in the melting zone with the consequent fuel economy and a more compact and convenient arrangement
15 of the furnace hearth than has hitherto been the usual practice.

In the accompanying exemplary drawings, Figure 1 is a side elevation of a cupola in which my invention is embodied in one
20 form; and Fig. 2 is a vertical section through this furnace on the line 2--2, Fig. 1.

The cupola shown comprises an outer supporting shell 10, with lining 11 of refractory material conveniently employed. The usual
25 charging aperture 12 is provided in the upper portion of the furnace through which the charge is introduced, while the exhaust gases pass out through the chimney 13 in usual manner.

30 The oxygen employed for the combustion of the fuel in furnaces of this character is commonly supplied by a blast which is led into the furnace through tuyers arranged in the lower portion thereof. Ordinarily this
25 blast is not preheated and the furnace temperature is consequently chilled more or less by the blast. In some instances an attempt has been made to preheat the blast, but these have not heretofore proven satisfactory for
35 one reason or another. The present arrangement has been effectively put into practice with resulting great economy of fuel in the reduction of a given charge.

The present system consists in leading the
45 blast from the blower, diagrammatically shown at 14, to the wind box 15 through passages heated by the furnace and leading directly to the wind box and tuyers. In the form shown, the heating passages comprise
50 radiation rings 16 and 17 built into the furnace body and preferably provided with radiation fins 18 to increase their radiation surface. The inner faces of these rings are flush with the inner face of the furnace lining, while the casing 11 incloses the rings thus forming annular heating channels in the body of the furnace. It will be noted

that the lower ring 17 is of greater height than the upper ring 16, and thus accommodates the increased volume of the air due to
60 its expansion on heating. The blast from the blower 14 is conducted to one side of the ring 16, through the pipe 19, passes around the ring on both sides of the furnace and discharges heated to the pipe 19 which leads
65 the blast to one side of the ring 17 around which it passes in similar manner to pipe 20 through which it is led to the wind box 15. The number of rings may obviously be varied as desired, and the pipes and exposed
70 walls of the passages are in any case preferably covered with suitable heat insulating material to prevent sensible loss of heat in transit.

The gases rising through the furnace from
75 the fuel contain a large percentage of carbon monoxid. This may be readily burned in the furnace, by opening ports 21 into the furnace chamber through the ring 17 through which a portion of the blast escapes into
80 the furnace, converting the carbon monoxid into carbon dioxid. Consequently these wasted gases by this device are converted into accessory fuel, the combustion of which serves not only to preheat the upper portion
85 of the charge, but also to heat the upper ring or rings 16 to a higher temperature than would otherwise be secured. This lower ring 17 is preferably located at a point so low in the furnace that should the blast
90 be cut off, the heat might be sufficiently intense to injure the ring. Dampers 22 are consequently provided in supplemental air ports 23, which may be opened when the blast is cut off, thus permitting the ring to
95 cool.

The wind box 15 may be of any desired character, as may also the tuyers leading therefrom. I prefer however to carry the wind box around the furnace and open independent tuyers 23 therefrom, each twyer being provided with its independent controlling valve 24. By providing an independent valve 24 for each twyer, it is possible to cut off the blast at any twyer which
105 chances to become blocked, as may be observed through the sight apertures 25, thus permitting the obstructing material to be melted by the molten mass adjacent. The tuyers are preferably staggered around the
110 furnace and may be as numerous as desired.

The usual fore-hearth into which the cupola ordinarily discharges is arranged beside the furnace in front of the discharge from

the melting chamber. This arrangement is clumsy and causes several disadvantages which are obviated by the arrangement shown. In its stead I now provide a tilting hearth 26, arranged beneath the furnace into which the latter discharges. In the form illustrated to disclose my invention, I provide a swinging bottom 27 for the cupola, pivoted at 28, and forming the top of the 10 tilting hearth 26. This bottom is shaped to carry the bottom lining 29 of the cupola on its upper face and the arched top 30 of the tilting hearth, while a cooling air space 31 is preferably provided to prevent the over-heating of this portion of the apparatus. A 15 discharge passage 32 is formed to permit the flow of the molten charge from the cupola to the hearth 26. Any suitable means may be employed for holding the bottom 27 in closed position, for example readily freed side latches 33. Similarly the tilting hearth in closed position is supported at one side by the bottom 27 by any suitable means, diagrammatically illustrated by the clamp 34 20 engaging juxtaposed flanges on the bottom 27, and hearth 26. The tilting hearth is provided with a tapping channel 35, and slag spout 36. The hearth is pivoted at 37 and may be swung on its pivot by the operation 25 of a hand winch 38, and suitable gearing 39. A removable block 40 of refractory material completes the channel from the cupola to the hearth, and is provided with an opening 41 which is normally closed by a plug 35 of clay, but which may be opened to observe the condition of the channel and to clear it, if need be. This arrangement of the hearth is of considerable practical value 40 since it permits a saving in the coke bed used for lighting the cupola, and removes the molten metal from contact with the incandescent coke and from the action of the air 45 blast. Furthermore, it renders the cupola as a whole more compact than where the usual forehearth is arranged beside the furnace. It renders the interior of the furnace more accessible for repairing or renewing the lining: the channel from the cupola to the hearth is relatively short, is more easily 50 made and it can be readily and carefully repaired. The likelihood of burning through at this delicate portion of the furnace is therefore reduced.

Obviously my invention is not limited to 55 the precise structure shown which is to be regarded as merely illustrative.

I claim as my invention:

1. A cupola having an outer casing and an insulating lining therefor, a charging throat 60 in the upper portion of the cupola, a plurality of independent radiation rings embedded in the refractory lining and spaced apart therein at points below the charging throat, means for leading the blast from an upper ring to a lower ring, and means for

forcing a blast downward serially through said rings, substantially as described.

2. A cupola having an outer casing and an insulating lining therefor, a charging throat in the upper portion of the cupola, a plurality of independent radiation rings embedded in the refractory lining and spaced apart therein at points below the charging throat, each of said rings being provided with annular radiation fins 18, means for leading the blast from an upper ring to a lower ring, and means for forcing a blast downward serially through said rings, substantially as described.

3. A cupola having an outer casing and an insulating lining therefor, a charging throat in the upper portion of the cupola, a plurality of independent radiation rings embedded in the refractory lining and spaced apart therein at points below the charging throat, means for leading the blast from an upper ring to a lower ring, said lower ring having ports opening to the interior of the cupola, for the purpose described, and means for forcing a blast downward serially through said rings, substantially as described.

4. A cupola having an outer casing and an insulating lining therefor, a charging throat in the upper portion of the cupola, a plurality of radiation rings spaced apart and embedded in the refractory lining at a point below the charging throat, means for leading the blast from an upper ring to a lower ring, and means for forcing a blast downward serially through said rings, together with dampers for opening said lower ring to the surrounding air on the halt of the blast, for the purpose described.

5. A cupola having a fusion zone, twyers opening thereinto, a plurality of radiation rings built into and spaced apart in the stack of the cupola and piping exterior to the cupola connecting said rings in series and leading the blast from the lowermost ring 105 to the twyers, substantially as described.

6. A cupola having a fusion zone, twyers opening thereinto, a plurality of radiation rings built into and spaced apart in the stack of the cupola above the fusion zone, 110 piping exterior to the cupola connecting said rings in series and leading the blast from the lowermost ring to the twyers, substantially as described.

7. A cupola having a fusion zone, twyers 115 opening thereinto, a plurality of radiation rings built into and spaced apart in the stack above the fusion zone and means for forcing a blast through said rings serially downward to the twyers.

8. A cupola having a plurality of radiation rings built into the stack, the upper rings being of less volumetric capacity than the lower, for the purpose described.

9. A cupola having a fusion zone, twyers 120

opening thereinto, a plurality of radiation rings built into and spaced apart in the stack above the fusion zone and means for forcing a blast through said rings serially downward to the twyers, and ports in a lower ring opening to the interior of the stack to permit portion of the blast to enter the stack, for the purpose described.

10. A cupola having a fusion zone, twyers opening thereinto, a plurality of radiation rings built into and spaced apart in the stack above the fusion zone and means for forcing a blast through said rings serially downward to the twyers, and ports in a lower ring opening to the interior of the stack to permit portion of the blast to enter the stack, together with means for opening said ring to the surrounding air for cooling, substantially as described.

15. 11. A cupola having in its stack a pair of radiation rings spaced vertically apart together with piping connecting the same in series, each of said rings having an inner periphery adapted to lie flush with the inner face of the stack and outwardly extending annular radiation fins confined within the stack area, together with means for passing a blast of air through said rings in series to the twyers, substantially as described.

20. 12. A cupola having in its stack a pair of radiation rings spaced vertically apart together with piping connecting the same in series, each of said rings having an inner periphery adapted to lie flush with the inner

face of the stack and outwardly extending annular radiation fins confined within the stack area, ports in the lower ring opening to the interior of the stack, together with means for passing a blast of air through said rings in series to the twyers, substantially as described.

25. 13. As a new article of manufacture for use in a cupola, a radiation ring having inner and outer diameter corresponding substantially to that of the lining of the cupola stack, and outwardly extending annular radiation fins on said ring extending in the direction of travel of the air through the ring in adjusted position.

30. 14. As a new article of manufacture for use in a cupola, a radiation ring having inner and outer diameter corresponding substantially to that of the lining of the cupola stack, and outwardly extending annular radiation fins on said ring extending in the direction of travel of the air through the ring in adjusted position, said ring having ports opening through its inner periphery to the air channels on its outer face, for the purpose described.

In testimony whereof I have signed my name to this specification, in the presence of two subscribing witnesses.

PAUL EMILE AUGUSTIN CERIEYS.
